INTERCHANGEABLE ELECTRIC SWITCH

William C. Furnas, Batavia Township, Kane County, Ill., assignor to Furnas Electric Company, Batavia, Ill., a corporation of Illinois

Application October 21, 1949, Serial No. 122,667

5 Claims. (Cl. 200—16)

1

The present invention relates generally to improvements in the art of electrical control, and relates more particularly to improvements in the construction and operation of unitary switching devices for controlling the circuit in diverse electrical systems.

A primary object of the invention is to provide an improved electric control switch which is exceedingly simple, compact and durable in construction, and which is moreover highly efficient and accurate in operation.

A more specific object of this invention is to provide an improved electric circuit control unit which is extremely flexible in its adaptations, and which may be quickly and easily installed and utilized by a novice with utmost safety.

Another specific object of my invention is to provide an improved switch assemblage having a one piece molded body and composed of exceptionally few parts which may be readily interchanged to conform with diverse desired operating conditions and requirements.

Another specific object of my present invention is to provide a new and improved electric switch of the pusher or plunger actuated type which may be conveniently installed in any desired locality with minimum space requirements by means of a single screw, bolt or the like.

A further specific object of the present invention is to provide an improved electric switch assemblage composed of few parts, all of which may be readily manufactured and assembled at low cost and without need for special tools, and wherein all parts are readily accessible for inspection, replacement, or alteration.

An additional specific object of the present invention is to provide an improved manually or mechanically operable pusher type electric switch unit which may be accurately positioned for rapid and secure attachment to a supporting wall, and wherein the terminals and contacts may be accurately and inexpensively produced in quantity from sheet metal with the aid of punches and dies.

Still another specified object of the present invention is to provide an improved switch assemblage comprising, a body having a rear recess and outwardly open grooves in the side and top walls communicating with the recess, electric terminals receivable in certain of the grooves and having fixed contacts positionable within the recess, an actuating member extending into the recess, and a movable contact carried by the actuating member within the recess and co-operable with the fixed contacts.

2

These and other specific objects and advantages of my present invention will be apparent from the following detailed description.

A clear conception of the several features constituting my invention, and of the mode of constructing and utilizing a typical plunger actuated switch embodying the invention, may be had by referring to the drawing accompanying and forming a part of this specification, wherein like reference characters designate the same or similar parts in the various views.

Fig. 1 is a relatively large rear view of one of my improved switch units showing the terminals and fixed contacts arranged for controlling a particular circuit;

Fig. 2 is a similar rear view of the switch showing the terminals and contacts arranged for controlling the same circuit but from a different side;

Fig. 3 is a transverse vertical section through the assemblage, taken along the line 3—3 of Fig. 1;

Fig. 4 is another transverse vertical section through the unit, taken along the line 4—4 of Fig. 1;

Fig. 5 is a rear view of the improved switch showing the terminals and fixed contacts arranged for controlling a different circuit and with the contacts shown in their normally closed position;

Fig. 6 is another rear view of the switch embodying the terminal and contact arrangement of Fig. 5, but showing the contacts actuated to open position;

Fig. 7 is a like rear view of the switch with the terminals and fixed contacts arranged for controlling still another circuit and with the contacts shown in normally open position; and

Fig. 8 is a rear view of the switch arrangement of Fig. 7, but showing the contacts actuated to closed position.

While the invention has been shown and described herein as being especially applicable to a manually or mechanically operable pusher or plunger actuated switch adapted for mounting in a particular manner to control certain circuits, it is not desired or intended to unnecessarily restrict the scope or utility of the improved features by reason of such limited embodiment.

Referring to the drawings, the improved switch assemblage shown therein comprises, in general, a molded one-piece body 10 having a rear recess 11, the body 10 also being formed with an outwardly open groove 12 in each of the side walls 13 communicating with the recess 11 and out-

wardly open grooves 14 in the top wall 15 also communicating with the recess 11; an electric terminal 16 interchangeably receivable in either of the side wall grooves 12 and having a fixed contact 17 at an end thereof positionable within the recess 11; electric terminals 18, 19, 20, 21 each interchangeably receivable in either of the top grooves 14 and each also being respectively provided with fixed contacts 22, 23, 24, 25 positionable within the recess 11; an actuating member or plunger 26 extending into the recess 11; and a movable contact 27 carried by the member 26 within the recess 11 and cooperable with one or more of the fixed contacts 17, 22, 23, 24, 25, as will hereinafter more fully appear.

The unitary body 10 may be readily molded in a known manner from suitable insulating material; and in addition to the outwardly open grooves 12, 14 in the side and top walls 13, 15 respectively, an outwardly open groove 28 is provided in the medial portion of the bottom wall 29 for receiving the actuating member 26. As shown, the actuating member 26 is in the form of a plunger or elongated pusher slidably confined within the groove 28 with a portion projecting outwardly of the body 10 beyond the lower wall 29 and with a reduced portion 30 extending upwardly into the recess 11 for receiving and carrying the movable contact 27, the reduced end portion 30 of the actuating plunger 26 forming a medial shoulder 31 thereon. To aid in guiding and limiting the movement of the actuating member 26, means cooperable therewith, such as a lug 32 formed integral with the body 10 within the groove 28, is provided; and this lug 32 is cooperable in an obvious manner with a longitudinal slot or groove 33 provided in the larger portion of the member 26.

The movable contact 27 is preferably in the form of a plate or bar having a central aperture 34 adapted to be penetrated by the reduced portion 30 of the member 26 with means being provided for retaining the contact plate 27 in position thereon for movement with the member 26, preferable retaining means being shown as comprising a stop 35 in the form of a cross-head penetrating an aperture 36 in the reduced portion 30 of the member 26 above the contact 27 and means, such as a compression spring 37, cooperable with the shoulder 31 and with the bottom of the contact 27 for constantly resiliently urging the same toward and against the cross-head 35. The spring 37 is of sufficient length so as to remain under compression at all times, but to aid in positioning the same, a pair of positioning lugs 38 may be formed on the member 26 adjacent the shoulder 31 as shown in Figs. 1 to 4. Means are also provided for constantly resiliently urging the actuating member 26 and contact 27 in one direction; and in the assemblage shown herein, such means comprises a compression spring 39 embracing the end of the reduced portion 30 of the member 26 and coacting at one end with the cross-head 35 and at the opposite end with the top wall of the recess 11, the recess being preferably formed with an upper reduced portion forming a confined passage or chamber 40 for the spring 39 which acts to return the member 26 and contact 27 carried thereby to lowermost position.

The switch assemblage thus described may be provided with a rear cover plate if desired or it may be mounted directly to a support 41 as shown in Fig. 4 with the aid of a screw or bolt 42 or the like adapted to penetrate a countersunk

hole 43 in the body 10; and while two such holes 43 are shown as being provided, the unit may be securely fastened to the support 41 or the like with only a single screw which may be utilized with either aperture 43 in the most convenient manner. To further facilitate positioning of the unit on the support 41, I prefer to form the body 10 with rare side wall notches 44 which are adapted to coact with projections or lugs which may be provided on the support 41; and to further aid in properly positioning and retention of the terminals 16, 18, 19, 20, 21 in place, the body 10 may be provided with positioning blocks 45 within the recess 11, as shown. The actuating member 26, as well as the body 10, may be readily molded of any suitable non-conducting material; and the movable contact 27, cross-head 35 and the various forms of interchangeable terminals 16, 18, 19, 20, 21 may be quickly produced of sheet metal with the aid of punches and dies and with the usual terminal attaching screws 46 being provided at the projecting ends of the terminals.

In assembly and operation of the unit, the proper terminals for the given circuit to be controlled are first applied within the proper grooves of the body 10. For example, in a three wire circuit requiring a so-called single pole double throw, the terminals 18, 19, are positioned in the grooves 14 and a single terminal 16 is positioned within the groove 12 as shown in Fig. 1; and if it is desired to mount the unit with the terminal 16, extending from the opposite side of the body 10, the terminals 16 and 18, 19 are interchanged in their respective receiving grooves 12 and 14 as shown in Fig. 2. If a two wire circuit requiring a so-called single pole, single throw normally closed is to be controlled, a terminal 16 is positioned in one or the other of the grooves 12, depending on mounting requirements, and a terminal 20, is positioned within the proper groove 14 as shown in Fig. 5. If, however, a two wire circuit requiring a single pole, single throw normally open is to be controlled, the terminals 18, 21, are positioned within the grooves 14 with the grooves 12 being left empty. In all of the arrangements herein illustrated and described, the contacts 17, 22, 23, 24, and/or 25, of the terminals utilized in the particular instance, are obviously fixedly positioned within the recess 11; and the terminals 16 may of course be interchangeably utilized in either of the grooves 12 with the terminals 18, 19, 20, and 21 likewise being capable of interchangeable utilization in either of the grooves 14 depending upon the conditions. The spring 37 is then placed in position over the reduced portion 30 of the member 26, and the movable contact 27 is thereafter applied to this reduced portion 30 with the cross-head or stop 35 then being positioned within the aperture 36 to retain the spring and contact 27 in position. The spring 39 may then be applied to the reduced end portion 30 of the member 26 above the cross-head 35; and with the spring 39 compressed, the actuating mechanism is then placed in position within the body 10 with the spring 39 resting against the upper wall of the recess 11 in the extension 40 thereof and under compression so as to constantly urge the actuating member downwardly. The actuating member 26 is of course slidable within the groove 28 with the lug 32 coacting with the slot 33, formed in either one or both sides of the member 26, to guide such member in its movement. The movable contact is accordingly normally in lowermost

position due to the action of the spring 39 and this contact 35 may be raised by pushing upwardly on the member 26, and upon release of upward pressure on such member, the spring 39 will obviously return the contact 27 to normal lowermost position.

From the foregoing detailed description it is believed apparent that my present invention contemplates provision of a unitary switch assembly which is exceptionally simple and compact in construction and exceedingly accurate, flexible and efficient in operation and which moreover is composed of very few parts which might require replacement or repair. The molded body is extremely durable and forms an effective protective housing for the switch arrangement, and the assemblage may be readily mounted to any desired supporting structure by means of a single screw 42 adapted to penetrate either of the counter sunk holes 43 in the body 10. The various terminals may be quickly and inexpensively formed of sheet metal with the aid of a press, and the respective contacts 17, 22, 23, 24 and 25 may be riveted or otherwise applied thereto. The several parts of the assemblage are interchangeable in an obvious manner with the actuating member 26 even being applicable from either side thereof to the groove 28. The assemblage is composed of so few parts and is capable of being dismantled and reassembled in such a rapid manner by a novice that the switch has extremely wide application, and it may be used not only for manual operation but also for actuation by mechanical or other means in diverse control systems. The improved switches may be manufactured in large quantities in a rapid manner for sale at extremely low cost, and units embodying the invention have, in fact, proven highly successful in actual use.

It should be understood that it is not desired or intended to limit this invention to the exact details of construction or to the precise mode of use, herein shown and described, for various modifications within the scope of the appended claims may occur to persons skilled in the art to which this invention pertains; and it is also contemplated that the various descriptive terms used herein shall be given the broadest possible interpretation consistent with the disclosure.

I claim:

1. In an electric switch, a unitary body formed of insulation and having a rearwardly open recess bounded by walls provided with rearwardly and laterally open grooves connecting the recess with the exterior of the body, electric terminals snugly frictionally confined at their medial portions within certain of said grooves and each having a fixed contact at its inner end disposed within said body recess while its outer conductor attachment end projects externally of the body, a unitary elongated plunger also formed of insulation and having its mid-portion slidably confined within another of said grooves while its inner end is reciprocable within said body recess between said fixed contacts and its outer end projects externally of the body, and movable contacts carried by said inner plunger portion and being cooperable with said fixed contacts within said body recess, all of said terminals and contacts and said plunger being freely removable from the rear of said body.

2. In an electric switch, a unitary body formed of insulation and having a rearwardly open recess bounded by walls provided with rearwardly and laterally open grooves connecting the re-

cess with the exterior of the body, electric terminals snugly frictionally confined at their medial portions within certain of said grooves and each having a fixed contact at its inner end disposed within said body recess while its outer conductor attachment end projects externally of the body, another of said grooves having an integral lug projecting from the bottom thereof, a unitary elongated plunger also formed of insulation and having its mid-portion slidably confined within said other groove and provided with a longitudinal slot cooperable with said lug while its inner end is reciprocable within said body recess between said fixed contacts and its outer end projects externally of the body, and movable contacts carried by said inner plunger end and being cooperable with said fixed contacts within said body recess.

3. In an electric switch, a unitary body formed of insulation and having a rearwardly open recess bounded by walls provided with rearwardly and laterally open grooves connecting the recess with the exterior of the body, electric terminals snugly frictionally confined at their medial portions within certain of said grooves and each having a fixed contact at its inner end disposed within said body recess while its outer conductor attachment end projects externally of the body, another of said grooves having an integral lug projecting from the bottom thereof, a unitary elongated plunger also formed of insulation and having its mid-portion slidably confined within said other groove and provided with a longitudinal slot cooperable with said lug while its inner end is reciprocable within said body recess between said fixed contacts and its outer end projects externally of the body, and movable contacts carried by said inner plunger end and being cooperable with said fixed contacts within said body recess, said slot coating with said lug to limit the movement of the plunger and all of said terminals and contacts and said plunger being freely removable from the rear of said body.

4. In an electric switch, a unitary body formed of insulation and having a rearwardly open recess bounded by walls provided with rearwardly and laterally open grooves connecting the recess with the exterior of the body, electric terminals snugly frictionally confined at their medial portions within certain of said grooves and each having a fixed contact at its inner end disposed within said body recess while its outer conductor attachment end projects externally of the body, a unitary elongated plunger also formed of insulation and having its mid-portion slidably confined within another of said grooves while its outer end projects externally of the body and its inner end is of reduced transverse cross-section and is reciprocable within said body recess between said fixed contacts, movable contacts tiltably mounted upon said reduced inner end portion of said plunger and being cooperable with said fixed contacts, and a helical compression spring interposed between said movable contacts and one of said body walls and embracing said inner plunger end portion within said recess.

5. In an electric switch, a unitary body formed of insulation and having a rearwardly open recess bounded by walls provided with rearwardly and laterally open grooves connecting the recess with the exterior of the body, electric terminals snugly frictionally confined at their medial portions within certain of said grooves and each having a fixed contact at its inner end disposed within said body recess while its outer conductor attachment

7
end projects externally of the body, a unitary elongated plunger also formed of insulation and having its mid-portion slidably confined within another of said grooves while its outer end projects externally of the body and its inner end is of reduced transverse cross-section and is reciprocable within said body recess between said fixed contacts, movable contacts tiltably mounted upon said reduced inner end portion of said plunger and being cooperable with said fixed contacts, 10 and a helical compression spring interposed between said movable contacts and one of said body walls and embracing said inner plunger end portion within said recess, all of said terminals and contacts and said plunger and spring being freely 15 insertible within and removable from the open rear of said body.

WILLIAM C. FURNAS.
